(57) **CLAIM**

The ornamental design for a vehicle mat set as shown and described.

DESCRIPTION

FIG. 1 is a perspective view of a first embodiment of a vehicle mat set showing my new design;

FIG. 2 is a perspective view of the left driver's seat footrest thereof;

FIG. 3 is another perspective view of the left driver's seat footrest thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 shown in FIG. 2;

FIG. 11 is a perspective view of the right front passenger seat footrest thereof;

FIG. 12 is another perspective view of the right front passenger seat footrest thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a perspective view of the rear seat footrest thereof;

FIG. 20 is another perspective view of the rear seat footrest thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a top plan view thereof;

FIG. 26 is a bottom plan view thereof;

FIG. 27 is a perspective view of a second embodiment of a vehicle mat set showing my new design;

FIG. 28 is a perspective view of the left front passenger seat footrest thereof;

FIG. 29 is another perspective view of the left front passenger seat footrest thereof;

FIG. 30 is a front elevational view thereof;

FIG. 31 is a rear elevational view thereof;

FIG. 32 is a left side elevational view thereof;

FIG. 33 is a right side elevational view thereof;

FIG. 34 is a top plan view thereof;

FIG. 35 is a bottom plan view thereof;

FIG. 36 is a perspective view of the right driver's seat footrest thereof;

(Continued)

FIG. 37 is another perspective view of the right driver's seat footrest thereof;
 FIG. 38 is a front elevational view thereof;
 FIG. 39 is a rear elevational view thereof;
 FIG. 40 is a left side elevational view thereof;
 FIG. 41 is a right side elevational view thereof;
 FIG. 42 is a top plan view thereof;
 FIG. 43 is a bottom plan view thereof; and,
 FIG. 44 is an enlarged view of portion 44 shown in FIG. 36. The dash-dash broken lines in the drawings depict portions of the vehicle mat set that form no part of the claimed design. The dot-dash broken lines represent boundaries of the enlarged portions and form no part of the claimed design.

1 Claim, 44 Drawing Sheets
